(57) **CLAIM**

We claim the ornamental design for a sprinkler controller, as shown and described.

DESCRIPTION

FIG. 1 is an isometric view of a sprinkler controller.

FIG. 2 is a front elevation view of the sprinkler controller of FIG. 1.

FIG. 3 is a right side elevation view of the sprinkler controller of FIG. 1.

FIG. 4 is a left side elevation view of the sprinkler controller of FIG. 1.

FIG. 5 is a top plan view of the sprinkler controller of FIG. 1.

FIG. 6 is a bottom plan view of the sprinkler controller of FIG. 1; and,

FIG. 7 is a rear elevation view of the sprinkler controller of FIG. 1.

The broken lines illustrate unclaimed portions of the sprinkler controller that form no part of the claimed design.
